UNITED STATES PATENT OFFICE

LESTER A. PERKINS AND ALBERT C. WILSON, OF CENTERVILLE, IOWA

DESIGN FOR A MILK CAN LID

Application filed September 12, 1932. Serial No. 44,820. Term of patent 7 years.

To all whom it may concern:

Be it known that we, LESTER A. PERKINS and ALBERT C. WILSON, citizens of the United States, residing in Centerville, in the county of Appanoose and State of Iowa, have invented a new, original, and ornamental Design for Milk Can Lids, of which the following is a specification, reference being had to the accompanying drawing, forming a part thereof.

Fig. 1 is a top plan view, and Fig. 2 is a side sectional view of a milk can lid, showing our new design.

We claim:

The ornamental design for a milk can lid, substantially as shown.

LESTER A. PERKINS.
ALBERT C. WILSON.
